UNITED STATES PATENT OFFICE.

NEWTON KELSAY, OF EVANSVILLE, INDIANA.

DESIGN FOR HAMES.

SPECIFICATION forming part of Design No. 19,288, dated August 27, 1889.

Application filed June 19, 1889. Serial No. 314,866. Term of patent 3½ years.

To all whom it may concern:

Be it known that I, NEWTON KELSAY, a citizen of the United States, and a resident of Evansville, in the county of Vanderburg and State of Indiana, have invented and produced a new and original Design for Hames; and I do hereby declare that the following is a full, clear, and exact description of the invention, which will enable others skilled in the art to which it appertains to make and use the same.

My design has relation to hames; and it consists in the peculiar configuration of the top part of the same, as will be hereinafter more fully described and claimed, reference being had to the accompanying drawings, in which—

Figure 1 represents a front view of a pair of pawls embodying my design, and Fig. 2 represents a vertical section of a part of one of the hame-bows. Fig. 3 represents a perspective view of one of the balls at the top of the bows.

The leading feature in my design consists

in the shape of the tops of the hame-bows A, which form a rounded part or ball B on the upper end of each, overlapping the upper 25 straight part C, and merging on the other side gradually into the sweep D of the outside. By this design a very neat and symmetrical appearance is given to the hames as a whole. This upper rounded part B, which constitutes 30 my design, may, if desired, be suitably ornamented by gilding, carving, or in any other suitable and appropriate manner.

What I claim is—

The design for hames herein described and 35 illustrated in the accompanying drawings.

In testimony that I claim the foregoing as my own I have hereunto affixed my signature in presence of two witnesses.

NEWTON KELSAY.

Witnesses:
